CLAIM

The ornamental design for an oven range as shown and described.

DESCRIPTION

1. Oven range
- 1.1 : Perspective
- 1.2 : Front
- 1.3 : Back
- 1.4 : Left
- 1.5 : Right
- 1.6 : Top
- 1.7 : Bottom
- 1.8 : Exploded

The broken lines depict portions of the oven range that form no part of the claimed design; the panel at the front bottom part of the subject design can be replaced according to the user's preference, as shown in reproduction 1.8; reproduction 1.8 is an exploded view of reproduction 1.1 showing the

(Continued)

state that the panel at the front bottom part of the subject design is being separated for replacing.

1 Claim, 8 Drawing Sheets
